GARMENT PRESSER

Carl T. Allme, Meadville, Pa., assignor to Spaide
Shirt Company, a corporation of Penn-
sylvania

Application July 23, 1936, Serial No. 92,121

2 Claims. (Cl. 38—28)

My invention relates to garment-pressing machines, and consists in improvements in the machine disclosed in my co-pending application for Letters Patent Serial No. 36,816, filed August 19, 5 1935.

In the accompanying drawings Fig. I is a fragmentary view of the machine in side elevation and in vertical section; Fig. II is a sectional view of the driving mechanism of the machine, taken on the plane II—II of Fig. I, and shown on larger scale; and Fig. III is a view in vertical section, and on the scale of Fig. II, of a particular locking device for the driving mechanism.

A pressing machine of the sort to which my invention is directed consists in a vertically reciprocable pressing head and a series of work-supporting pads. The pads are laterally interconnected in closed or endless series, and means are provided for advancing such endless series 20 step-by-step, whereby the pads are brought, one after another, into a position of momentary rest beneath the head. The attendant places garments to be pressed upon the pads, as they advance into such position, and, in the interval 25 between each pad-advancing movement, the pressing head automatically descends and presses the garment lying upon the pad beneath it. Upon remaining in pressing engagement with the garment for a predetermined interval of time, the 30 pressing head is automatically raised, and the series of pads is moved a step forward, carrying the pressed garment from beneath the head, and moving another into pressing position.

In Fig. I of the drawings, the reference numeral 1 is applied to the frame of the machine. The frame is only fragmentarily indicated, but it will be readily understood (keeping in mind the showing in my co-pending case) that the frame includes on each side of the machine two parallel, 40 vertically spaced-apart angle members 1a, 1a; at each of the opposite ends of and between such paired angle members a roll 6 is mounted, and the endless work-carrier (not shown) is trained over such rolls and extends between the rolls in upper and lower reaches that are guided by and 45 supported upon the angle members 1a. One of the rolls 6, the roll appearing in Figs. I and II, is connected by suitable gearing (not shown) to a shaft 57, and, as presently will appear, mechanism is provided for intermittently rotating the 50 shaft 57 and roll 6 through such intervals that the work-carrier is advanced in the manner alluded to.

The mechanism for intermittently rotating the 55 shaft 57 is adapted also to effect the alternate

descent and rise of the pressing head. The invention lies in particular refinements and elaborations in such mechanism, and, for the sake of simplicity and clarity of illustration, the pressing head, the work-carrier, and other particular parts of the apparatus, common both to my present machine and the one disclosed in my co-pending case, have not been illustrated herein. Suffice it to say that the pressing head is mounted upon the upper ends of two shafts 80 and 81, 10 rigidly integrated by cross-bars 87 and 88, and mounted for vertical reciprocation in stationary bearing blocks 84 and 85, and that said mechanism is effective to move the shafts in such manner that the pressing head descends into engagement with the work in the intervals between successive advances of the work-carrier. Upon holding the head in pressing engagement with the work for a predetermined and adequate interval of time, the mechanism operates first to 20 move the shafts 80, 81 upward and lift the head from the work, and then to rotate shaft 57 and effect the advance of the work-carrier through such interval that the pressed garment is moved on and an unpressed garment is moved into position of registry beneath the head. 25

Turning to a detailed consideration of the driving mechanism: A toggle, comprising two links 40 and 41 mutually pivoted at their inner ends to a connecting rod 42, is connected to a horizontally reciprocable cam-plate 45; that is, to an arm 45b extending from such cam-plate and projecting with sliding fit through a bearing 2 in the wall of a housing 44 that encloses the driving mechanism, it being noted that the side 30 cover-plate 44c (Fig. II) of the housing is removed in Fig. I. The outer end of link 40 is pivotally connected to a stationary frame portion 1b of the machine, while the corresponding end of link 41 is pivotally secured to the rigid 35 cross-bar 88 that interconnects the shafts 80 and 81. And the connection of the connecting rod 42 with the slide-arm 45b is made in a cross-head 43. 40

A shaft 46, mounted in the walls of housing 44, 45 is geared to an electric motor 50 for continuous rotation; two radial arms 52 and 53 are secured on shaft 46, and between these arms the cam-plate 45 is mounted and laterally supported, as shown in Fig. II, it being further perceived (in 50 Fig. I) that the cam-plate includes a horizontal slot 45a, through which the shaft 46 extends, and by virtue of which horizontal reciprocation of the cam-plate is permitted. As viewed axially of the shaft 46, the arms 52 and 53 extend angu- 55

larly to one another (Fig. I), and the arm 52 carries a pin 54 which is axially movable transversely of the distal end of the arm, for cooperation with the cam-plate. The other arm-arm 53—carries a pin or roller 55 that cooperates with a Geneva stop or cam 56 secured on shaft 57. During each rotation of the constantly driven shaft 46, the arms 52, 53 and their associated elements effect in accurately time sequence a quarter rotation of the Geneva cam and a complete reciprocation of the cam-plate 45. The driving gearing between the shaft 57 and the roller 55 is such that one quarter revolution of the Geneva cam effects the advance of the work-carrier through the desired interval, already mentioned, and, as will more fully appear below, each horizontal reciprocation of the cam-plate 45 effects a complete operation of the pressing head. Thus, both the work-carrier and the pressing head derive their operating movements from the continuously rotating shaft 46. Manifestly, it is thus possible accurately and positively to coordinate the step-by-step advance of the work-carrier with the vertical reciprocations of the pressing head.

The Geneva cam 56 in known way is provided with four radial slots 66. When the arm 53, rotating counterclockwise, reaches its uppermost position and swings downward, the roller 55 carried thereby enters the outer end of one of the slots 66 in the Geneva cam—specifically the slot 66a in Fig. I is in position to receive the roller. Rotation of the shaft 46 and arms 52, 53 continuing unabated, the engagement of the roller 55 in the slot of the Geneva cam causes such cam to rotate clockwise through ninety degrees, or, graphically, to such position that the slot 66a reaches the position of slot 66b in Fig. I. As the parts reach such position, the roller 55 is by the rotating arm 53 swung from the slot, and a semi-cylindrical disc 64, integrated with the arm 53, enters the adjacent one of the four recesses 65 provided between the slots 66 in the periphery of the Geneva cam. In known way the engagement of the disc 64 in the recess 65 secures the Geneva cam against rotation. The disc 64 rotates in unison with the continuously rotating arm 53, but the Geneva cam 56 and shaft 57 remain at rest so long as any portion of the disc 64 remains in engagement with recess 65. Thus, the shaft 57 is positively turned through a fraction of a rotation and arrested, and, manifestly, such a fractional rotation of the shaft 57 is effected during each rotation of the continuously driven shaft 46.

In that fraction of each rotation of the continuously driven shaft 46, in which the Geneva cam is turned through ninety degrees, the cam-plate 45 remains at rest in the position illustrated in Fig. I. In such position of the cam-plate, the pressing head will be understood to be lifted clear of the work-carrier. In the fraction of each revolution of the shaft 46 in which the Geneva cam rotates, the pin 54 is held in retracted position in the end of rotating arm 52, and in such position the pin does not engage the cam-plate 45. More specifically, the pin carries heads 54a and 54b at its opposite ends; a spring 60 (Fig. II), arranged between head 54b on the pin and side 52a of the arm, serves to hold the pin in such position that its head 54a (shown extended in Fig. II) is retracted or nested within a pocket 52b provided in the distal end of the arm.

Two cams 61 and 63 are mounted on the wall 78 44a of the housing 44. These cams lie spaced

apart in the circular path through which the pin 54 is carried by rotating arm 52.

As the roller 55 is swung from engagement with the Geneva cam and the work-carrier comes to rest at the end of an advance, the head 54b moves in circular path into sliding engagement with the cam 61, and shifts the pin 54 against the restraint of spring 60 into the position illustrated in Fig. II, with the head 54a of the pin projecting in such manner as to engage a leg 45e on the cam-plate. Due to such engagement the rotating arm 52 shifts the cam-plate to the right (Fig. I), whereby the toggle linkage 40, 41, 42 is shifted into dotted line position, forcing the shafts 80, 81 downward and thereby carrying the pressing head into pressing position. It will be noted that the common pivotal joint of the links 40, 41 is moved past center and into abutment with an adjustable stop 62. Thus, the linkage tends to remain in its dotted line position, holding the 20 pressing head in engagement with the work. As the linkage 40, 41, 42 enters such position the pin 54 passes in its circular path from engagement with the cam 61, and the spring 60 retracts the pin, so that there is no mechanical interference 25 between the rotating arm 52 and the cam plate. When the outer end of rotating arm 52 reaches the top of its path of rotation, the cam 63 effects again the extension of the pin 54, whereby the head 54a of the pin engages a leg 45d on the 30 cam-plate, and powerfully carries the linkage 40, 41, 42 from dotted-line to full-line position, and thus raises the head from engagement with the work immediately before the roller 55 on arm 53 enters carrier-advancing engagement with the 35 Geneva cam. The pin 54 passes from engagement with the cam 63, as the parts move into full-line position.

It will be understood that the head remains in pressing position during the interval in which 40 the pin 54 is being carried from engagement with cam 61 to cam 63. Desirably, the duration of this interval is adjustable, and the adjustment is effected by means of the cams 61 and 63. The cams are adapted for adjustment relatively 45 to one another and in the circular path followed by the pin 54. As shown in Fig. II, each cam has a tongue-and-groove engagement 82 with the housing wall 44a; in plan the tongues and grooves comprise arcs of the circle followed by the pin 54, 50 and each cam is pivotally connected to the end of a threaded stem 86 that projects through a sleeve-nut 83 secured in the side wall 44b of the housing, as shown in Fig. I. By rotating the nuts in one direction or the other, the stems 86 55 are moved axially inward or outward, and such shifting of either stem adjusts the position of the associated cam (61 or 63) peripherally of circular path followed by the pin 54. Thus, the circumferential interval between the cams may be 60 adjusted, and the effective time of engagement of the pressing head with the work regulated. Additionally, the adjustment of the cams 61, 63 permits regulation of the timing between the operations of the work-carrier and pressing head. 65

As has been already mentioned, the pressing head is sustained in elevated position during that portion of each rotation of shaft 46 in which the arm 53 cooperates with the Geneva cam 56 in effecting advance of the work-carrier. And, as 70 disclosed in my co-pending case, means are provided for temporarily locking the pressing head in such elevated position. In accordance with my present invention the means to this end consist in a locking device that is released automatically, 75

in response to the positive movement of the head-reciprocating mechanism. Advantageously, such means consist in a pin 70 cooperating with the cross-head 43. As shown in detail in Fig. III, the 5 pin 70 is mounted for limited vertical movement in a cylinder 2a, integral with bearing 2; a socket 43a is found in the upper face of the cross-head, and the lower, round end of the pin is by a spring 71 held in the socket. The engagement of the pin in 10 the socket is adequate to secure the parts against unintended movement, with the pressing head in elevated position. When, however, positive head-operating thrust is applied to the cross-head, the pin yields upward against spring tension and the 15 cross-head is released for reciprocation. As the slide-arm 45b moves from locked position (full-line position, Fig. I) through a single reciprocation, the pressing head is lowered, held against the work for an interval, and then raised. As the 20 slide-arm returns to the initial point in its range of reciprocation, the tip of pin 70 again enters the socket 43a in the cross-head and serves to secure the parts in positions of rest, until the pin 54 in the rotating arm 52 again engages the cam- 25 plate 45 and applies head-operating thrust to the slide-arm 45b.

It will be understood that the above-described apparatus may be modified within the terms of the following claims, without departing from the 30 essence of the invention.

I claim as my invention:

1. In garment-pressing apparatus including a pressing head, a garment-supporting surface, and means for intermittently moving said head into pressing position on said surface and maintaining it in such position for a sufficient interval of time, said means including a reciprocating head-moving member, a rotary member, an element carried by said rotary member and adapted to be extended and retracted relatively to said rotary member for engagement with said reciprocating member, and a pair of cam-blocks arranged in arcuately spaced relation for effecting the extension of said element, one of said cam-blocks being mounted for movement in an arcuate path substantially parallel to the path 15 through which said element is moved by said rotary member, the combination of means for adjusting said last-named cam-block in said arcuate path relatively to the other of said cam-blocks, whereby the point at which said element 20 is extended in the circular sweep of the rotary member may be varied and the interval of time between successive extensions of the element may be regulated, to control the operation of the pressing head, as described. 25

2. The structure of the next-preceding claim, in which the block-adjusting means comprises a stem articulated to a block and axially adjustable in a line intersecting the arcuate path of block adjustment. 30

CARL T. ALLME.
